[57] CLAIM

The ornamental design for a hanger for pants, skirts or the like, substantially as shown and described.

DESCRIPTION

FIG. 1 is a front elevational view of a hanger for pants, skirts or the like showing my new design, in its unlatched condition;

FIG. 2 is a top plan view thereof;

FIG. 3 is a bottom plan view thereof;

FIG. 4 is a left side elevational view thereof;

FIG. 5 is a right side elevational view thereof;

FIG. 6 is an enlarged sectional view taken in the direction of the arrows on line 6—6 of FIG. 1;

FIG. 7 is a fragmentary rear elevational view of the hook taken in the direction of the arrows on line 7—7 of FIG. 6;

FIG. 8 is a sectional view taken in the direction of the arrows on line 8—8 of FIG. 6;

FIG. 9 is an enlarged sectional view taken through the lower garment bar of FIG. 1;

FIG. 10 is a fragmentary front elevational view of a second embodiment of the design of FIG. 1, the only difference being the configuration of the hook area;

FIG. 11 is a fragmentary front elevational view of a third embodiment of the design of FIG. 1, the only difference being in the configuration of the hook area;

FIG. 12 is a fragmentary front elevational view of a fourth embodiment of the design of FIG. 1, the only difference being in the configuration of the hook area;

FIG. 13 is a fragmentary sectional view taken in the direction of the arrows on line 13—13 of FIG. 12.

FIG. 6.FIG. 7.FIG. 8.FIG. 9.FIG. 10.FIG. 12.FIG. 13.FIG. 11.
